TRAFFIC BARRIER

Henry M. De Noble, Lubbock, Tex.

Application July 13, 1954, Serial No. 31,408

Term of patent 7 years

(Cl. D72—1)

Fig. 1

To all whom it may concern:

Be it known that I, Henry M. De Noble, a citizen of the United States, residing at Lubbock, in the county of Lubbock and State of Texas, have invented a new, original, and ornamental Design for a Traffic Barrier, of which the following is a specification, reference being had to the accompanying drawing, forming part thereof.

Fig. 1 is a perspective view of a traffic barrier showing my new design;

Fig. 2 is a side elevational view thereof; and

Fig. 3 is an end elevational view of the same.

I claim:

The ornamental design for a traffic barrier, as shown.
